LAP RETRUEING MACHINE

Robert S. Duke, Houston, Tex.

Application July 6, 1936, Serial No. 89,033

5 Claims. (Cl. 29—76)

This invention relates to a lap re-truing machine.

It is an object of the invention to provide a machine of the character described and specially designed for reshaping the spherical or toric surface of the lap, such as are used in lens grinding and polishing machines.

In the manufacture of lenses, such as optical lenses, a grinder is employed, one element of which comprises a lap having a grinding surface which is of the curve of the desired surface of the lens to be ground. As a result of use the active surface of the lap, be it either convex or concave, becomes misshapen from wear. It is an object of this invention to provide a re-truing machine wherein the grinding lap may be restored to its original curve or curves.

It is another object of the invention to provide a machine of the character described wherein the misshapen lap may be mounted and which is equipped with an abrasive surface arranged to cooperate with the lap and which is capable of the required adjustments to restore the active surface of the lap to the original curve or curves, the range of adjustment being such that a worn lap of any original spherical or toric surface may be restored for further use in lens grinding and polishing.

With the above and other objects in view, the invention has particular relation to certain novel features of construction, operation and arrangement of parts, an example of which is given in this specification and illustrated in the accompanying drawings, wherein:—

Figure 1 shows a side elevation of the lap re-truing machine partly in section.

Figure 2 shows a cross sectional view of the stand taken on the line 2—2 of Figure 1.

Figure 3 shows a side view partly in section, taken at right angles to the view shown in Figure 1.

Figure 4 shows a plan view.

Figure 5 shows a cross sectional view taken on the line 5—5 of Figure 3.

Figure 6 shows a fragmentary side view partly in section, showing a modified form of the machine, and

Figure 7 shows a fragmentary sectional view taken at right angles to the form shown in Figure 6.

Referring now more particularly to the drawings, wherein like numerals of reference designate same parts in each of the figures, the numeral 1 designates a suitable stand which is tubular in form and mounted on the base 2. Fitted

within the upper end of the stand there is a chuck 3 which is splined therein against rotation by the key 4. The upper end of this chuck extends above the stand and is upwardly tapered and blank as at 5 to fit into the socket 6 of the lap 6a to be ground. The tapering portion of the chuck has a lateral key 7 which is received in the keyway 8 of the shank of the lap whereby the lap is held against turning on the chuck. An intermediate portion 9 of the chuck is externally threaded and an adjusting nut 10 is threaded thereon and abuts the upper end of the stand whereby the chuck and the lap thereon may be vertically adjusted.

Vertically slidable on the support 1 there is a clamp 11 which is splined thereon by the spline 12. The free ends of the clamp 11 have the outwardly turned corresponding lugs 13, 13. A clamp screw 14 is fitted through one of said lugs and has a threaded connection with the other and the outer end of this screw has the grips 15, 15 whereby the screw may be turned to contract or expand the clamp 11. Laterally offset from, but rigidly secured to, said clamp there is the upstanding arm 16 and mounted on the upper end of this arm to pivot on a horizontal axis is the yoke 17. This yoke is mounted to pivot on the spindle 18 which is secured to the arm 16. One end of the yoke is formed into the counterweight 19 and secured to the other end of the yoke there is a vertical guide 20. Slidable on said guide and having a dovetailed connection therewith there is a wrist bearing 21 in right angular relation to the axis of the spindle 18.

A screw shaft 22 is mounted to swivel in a vertical bearing 23 at the upper end of the guide 20 and this shaft 22 has a threaded connection with the wrist bearing 21 whereby said bearing 21 may be adjusted vertically. The guide 20 carries a gauge 24 and the wrist bearing 21 is equipped with a pointer 25 whereby the point of adjustment of the bearing 21 may be approximately ascertained. For finer, or more accurate, adjustments the upper end of the bearing 23 is provided with a gauge 26 and the adjacent portion 45 of the shaft 22 is provided with a mark 27 to indicate the adjustment of the shaft. The shaft 23 is equipped with a handle 28 whereby it may be turned.

There is a crank arm 29 one end of which is formed into a wrist 30 which works in the bearing 21. The other end of this arm is arranged opposite the arm 16 and has a sleeve 31 provided to receive the lower end of the upstanding standard 32. The standard is secured in said

sleeve by means of suitable set screws 33. There is a file holder 34, one end of which is formed with a vertical bearing 35, preferably square in cross sectional contour, and which is vertically 5 slidable on the standard 32. The file holder may be secured at any point of adjustment on the standard by means of the set screw 36 which has a threaded connection with the wall of the bearing 35 and whose inner end is adapted to 10 bear against said standard. The outer end of the set screw 36 is equipped with a grip 37 whereby said set screw may be turned. The other end of the holder 34 is downwardly turned and provided with a lengthwise groove forming a seat 15 38 wherein the file 39 may be seated and secured by set screws 40 threaded through the wall of said seat.

On the standard 32 there is a gauge 41 for indicating the radius of the dioptric curvature 20 of the operative surface of the lap 6a and the bearing 35 has a side window 42 which carries the transverse indicating line 43.

When the surface of the lap becomes misshapen as a result of use it may be removed from the 25 lens grinding machine and mounted on the chuck 3 as shown in Figures 1 and 3. Before mounting the lap in place, however, the screw 14 is loosened and the clamp 11 elevated so as to move the holder 34 and file 39 elevated out of the way, and the 30 screw 14 may be then tightened to cause the clamp 11 to grip the stand 1 so as to hold the parts in elevated position. The lap 6a may then be mounted in place. The screw 36 may then be released and the file holder 34 adjusted with respect to the gauge 41 to give the desired radius of dioptric curvature, that is, the base curve and the screw 36 then tightened up to securely fasten the file holder to the standard 32.

The wrist bearing 21 is now adjusted in accordance with the particular contour desired for the toric surface of the lap. If said last mentioned bearing be adjusted into a common horizontal plane with the bearing of the yoke 17 and the file 39 be operated over the surface of the lap and 40 about said bearings, as axes, a segment of a spherical surface will be produced on the lap. If the wrist bearing 21 be adjusted out of the horizontal plane of the yoke bearing the surface produced by the file 39 on the lap will be varied 45 from a true spherical segment and will approach a cylindrical surface, the variation in the particular form of the toric surface produced depending upon the relative adjustment of the two axes.

The screw 14 is then loosened and the clamp 11 lowered until the file rests on the surface of the lap to be operated upon. The set screw 14 is then tightened up to cause the clamp to grip the stand.

As will be noted by an inspection of Figures 1 and 3, a wide range of adjustments has been provided for, to the end that any desired curvature of the operative face of the lap 6a may be produced. During the progress of the work the nut 10 may be adjusted from time to time, to hold the lap closely to the work. When the lap has 60 been ground to the desired contour it may be removed from the chuck ready for use in the lens grinder or polisher.

As shown the operative face of the lap 6a is convex. This will produce a concave face on the 70 lens ground thereon. If it be desired to produce a convex face on the lens, it is of course necessary that the operative face of the lap be concave as shown in Figure 6.

As shown in Figures 6 and 7 the holder 34a is 75 provided with a socket 44 to receive the shank

of the adjusting nut 10a. This nut is retained in the holder by means of the transverse pins 45 which are fitted through the annular groove 46 around said shank. The chuck 3a is threaded through the nut 10a and the lower end of this chuck is tapered as at 5a to fit in the socket of the lap 6b. The tapering portion of the chuck 5a has a lateral key 7 which is received by the keyway 8 of the shank of the lap 6b whereby said lap is held against turning on the chuck. The 10 lap 6b has a concave operative face 47.

In this form there is a fork 48 having a spindle 48a which is keyed in the upper end of the stand 1, as shown in Figure 6, and mounted in the fork there is a file, or other abrading member 39a. 15 This file 39a is of a general cylindrical contour and it is provided with the end spindles 49 which are mounted to rotate in the bearings formed in the arms of the fork 48. These spindles are held against rotation by the set screws 50, 50. The 20 surface of the abrading member 39a has the contour of a spherical segment and as the abrading surface becomes worn the member 39a may be partially turned from time to time by loosening the set screws 50 and upon making the adjustment again tightening them up.

The weight 19 hereinabove referred to has been provided for balancing the adjusting and grinding mechanism, hereinabove described, about the axis of the spindle 18.

What I claim is:

1. A machine of the character described comprising a stand, a yoke mounted on the stand to pivot on a horizontal axis, a standard, means for supporting the standard to pivot about a horizontal axis on the yoke, said supporting means being vertically adjustable, a work holder on the stand, a file holder vertically adjustable on the standard, a file on the file holder adapted to contact the work, means for fixing the file holder at any point of adjustment on the standard.

2. A machine of the character described comprising a stand, a vertically adjustable arm on the stand, means for fixing the arm at any selected point of adjustment, a yoke mounted to pivot on a horizontal axis on the arm, a vertically adjustable bearing on the yoke, means for adjusting said bearing relative to said axis, a standard support having a wrist mounted to pivot in said bearing, an upstanding standard on 50 said support, a work holder on the stand adapted to receive and support the work to be operated on, a file holder, means for fixing the file holder at any selected point of adjustment on the standard, a file on the holder in contact with the 55 work.

3. A grinding machine comprising a stand, a yoke mounted on the stand to pivot on a horizontal axis, a standard, means for supporting the standard to pivot about a horizontal axis on the 60 yoke, said supporting means being vertically adjustable, a work holder on the stand, a file holder vertically adjustable on the standard, a file on the file holder adapted to contact the work, means for fixing the file holder at any point of adjustment on the standard, and means for adjusting the work on the stand.

4. A machine of the character described comprising a stand, an arm adjustable longitudinally with respect to the stand, means for fixing the 70 arm at any selected point of adjustment, a yoke mounted to pivot on the arm on an axis at approximately right angles to the axis of the stand, a bearing on the yoke adjustable at approximately right angles to the axis on which the yoke 75

- 5 pivots, means for adjusting said bearing relative to said last mentioned axis, a standard support having a wrist mounted to pivot in said bearing, an upstanding standard on the support, a work holder on the stand adapted to receive and support the work to be operated on, a file holder, means for fixing the file holder at any selected point of adjustment on the standard and a file on the holder in contact with the work.
- 10 5. A lap re-truing machine comprising a stand, an arm adjustable longitudinally with respect to the stand, means for securing the arm at a selected point of adjustment, a yoke mounted to pivot on the arm on an axis at approximately 15 right angles to the axis of the stand, a bearing
- 5 on the yoke adjustable at approximately right angles to the axis on which the yoke pivots, means for adjusting said bearing relative to said last mentioned axis, a standard support having a wrist mounted to pivot in said bearing, an upstanding standard on said support, a work holder adapted to receive and support the work to be operated on, a file holder and a file thereon, one of said holders being located on the stand and the other being located on the standard and 10 means for fixing one of said holders at a selected point of adjustment on its support with the file in contact with the work.
